UNITED STATES PATENT OFFICE.

WILLIAM T. O'CONNOR, OF JACKSON, KENTUCKY.

AERIAL TORPEDO.

1,355,564.

Specification of Letters Patent. Patented Oct. 12, 1920.

Application filed May 10, 1920. Serial No. 380,196.

To all whom it may concern:

Be it known that I, WILLIAM T. O'CONNOR, citizen of the United States, residing at Jackson, in the county of Breathitt and 5 State of Kentucky, have invented certain new and useful Improvements in Aerial Torpedoes, of which the following is a specification.

The present invention relates to improvements in aerial torpedoes including in combination a main body structure, means to support the body structure in flight and means to propel the body portion in connection with other means and mechanisms to 15 regulate the explosion of the torpedo.

Various other objects and advantages of my invention will become apparent during the continuance of the following description.

20 In the drawings:

Figure 1 is a view in side elevation of my invention as completely assembled.

Fig. 2 is a view in longitudinal cross section of the body proper of the torpedo.

25 In reducing my invention to practice, I first provide a body portion in the form of a shell or casing 10 which is preferably constructed of metal such as malleable iron, the same tapering from its central portion to 30 pointed end portions as clearly shown in Fig. 2 of the drawings. Within the casing 10 are arranged partition members 11, 12 and 13 which divide the same in four compartments 14, 15, 16 and 17. The partition member 11 carries a bracket 18 that abuts the rear end of the shell 10 and carries a 35 percussion cap 19.

Other partition members 20 and 21 are arranged in the compartment 15 between the 40 partition members 12 and 13 thus forming other compartments 22 and 23. A driving motor 24 is carried within the compartment 15, storage batteries 25 are positioned in the compartment 23 and connected with the motor 45 by means of wires 26 while the compartment 22 is provided with a highly reinforced carrier 27 which supports and carries a time fuse 28. The shell 10 is provided with an opening 29 opposite the time fuse 28 for the purpose that will presently 50 appear.

A sleeve 30 extends longitudinally through the compartment 17 through the

partition 13 and is opened to the forward end of the shell 10 as clearly shown in Fig. 55 2. This sleeve accommodates the drive shaft 31 which extends from the motor 24. In order to support the shaft 31 suitable bearings 32 and 33 are provided in the sleeve 30.

The projecting end of the shaft 31 carries 60 a driving propeller 34 of conventional construction, the same being either of the two or four bladed type, such as occasion may require.

At its rear end the shell 10 is provided 65 with a wind guide 35 which may be secured in place by means of fastening members 36.

Throughout its length the shell 10 is provided with suitably spaced fastening members 37 to which are attached other fastening members carried by the gas bag 38. When inflated, the gas bag is designed to 70 support the torpedo while in flight.

It is contemplated to inflate the gas bag 38 with a very light explosive gas and to 75 fill the compartments 16 and 17 with T. N. T. such as shown at 39.

In operation when the gas bag 38 is inflated to a proper degree the motor 24 is started to operate the propeller 34 and the 80 torpedo released, the time fuse 28 having first been adjusted to the desired degree. The gas bag 38 causes the torpedo to rise from the ground or from the tower from which it is released while the propeller 34 85 propels the same forwardly and the guide 35 directs the same in flight. The exploding of the time fuse 28 sets off the gas bag 38. This takes away the supporting means for the torpedo and the rear end of the tor- 90pedo being the heavier causes the torpedo to turn into a vertical position and fall to the ground rear end first. The percussion cap 19 explodes upon contact with the ground thus causing an explosion of the entire tor- 95pedo.

What is claimed is:

1. In a torpedo of the character described a body portion containing an explosive material, a gas bag to support said body portion in flight, means to propel said body portion, means to explode said gas bag at a predetermined time, and a percussion cap to explode the explosive material in said body portion upon contact with the ground. 100 105

2. In a device of the character described

- a body portion, explosive material in said body portion, a propeller to propel said body portion in flight, means to drive said propeller, means to support said body portion in flight including the gas bag containing a light explosive gas, means carried by said body portion to explode said gas at a predetermined time, and a percussion cap

in said body portion to explode said explosive material upon contact with the ground. 10

In testimony whereof I affix my signature in presence of two witnesses.

WILLIAM T. O'CONNOR.
